UNITED STATES PATENT OFFICE

ANDREW S. KNAPP, OF BELLEVILLE, ILLINOIS, ASSIGNOR TO KNAPP-MONARCH COMPANY, OF BELLEVILLE, ILLINOIS, A CORPORATION OF MISSOURI

DESIGN FOR AN ELECTRIC COOKING OVEN

Application filed May 23, 1932. Serial No. 43,884. Term of patent 7 years.

To all whom it may concern:

Be it known that I, ANDREW S. KNAPP, a citizen of the United States, and a resident of Belleville, in the county of St. Clair and State of Illinois, have invented a certain new, original, and ornamental Design for an Electric Cooking Oven, of which the following is a specification, reference being had to the accompanying drawing, forming part thereof:

Figure 1 is a top plan view of an electric cooking oven embodying my new design.

Figure 2 is a front view of the same; and Figure 3 is a side view thereof.

I claim:

The ornamental design for an electric cooking oven substantially as shown.

Des Moines, Iowa, May 12th, 1932.

ANDREW S. KNAPP.
